FIREPLACE LIGHTER

Harvey V. Paulson, Penfield, and Wallace L. Liese, Kent, N.Y., assignors to Bernzomatic Corporation, Rochester, N.Y.

Filed Nov. 15, 1972, Ser. No. 306,656

Term of patent 14 years

Int. Cl. D7—08

U.S. Cl. D48—27 C

FIG. 1 is a top plan view of a fireplace lighter showing our new design;

FIG. 2 is a right side elevational view thereof;

FIG. 3 is a front elevational view thereof;

FIG. 4 is a left side elevational view thereof;

FIG. 5 is a bottom plan view thereof; and

FIG. 6 is a rear elevation view thereof, the lighter being broken away for convenience of illustration.

The indicia is shown in FIGS. 2, 3, 4 and 6 in broken lines for illustrative purposes only.

We claim:

The ornamental design for a fireplace lighter, as shown and described.
